RACK

Erwin Feibelman, New York, N. Y.

Application April 24, 1939, Serial No. 269,732

4 Claims. (Cl. 211—41)

This invention relates to stands or racks and more particularly to racks for use in connection with kitchen articles, as, for example, saucers, cups, plates or the like.

5 It is an object of the present invention to provide a rack of the above nature which securely holds and maintains in position bulky articles, preferably cups or the like.

It is another object of the present invention to 10 provide means for holding the articles with projected parts in staggered relation and in such a manner that slipping off of the articles is absolutely avoided.

Still another object of the present invention 15 resides in the provision of means for steadily supporting said rack on the kitchen board, table or any other suitable place.

It is a still further object of the present invention to provide a base forming part of said rack, 20 in which base there may be housed flat articles, as, for example, plates, saucers, knives, etc.

Yet, another object of the present invention contemplates the provision of means for easily manipulating said flat articles for their insertion 25 in and withdrawal from said rack.

It is a further object of the present invention to provide a combined saucer and cup portable rack, which is so constructed that it may be placed in any desired location and which may be 30 transported safely from one place to another with the various articles positioned therein.

It is a still further object of the invention to provide a rack for holding cups in stacked relation, provision being made for guidingly receiving 35 the ears of said cups for preventing shifting thereof during transportation.

Still another object of the invention resides in the provision of a rack having a cup retaining portion and a saucer retaining portion, both 40 the cups and saucers being respectively sustained in stacked relation, the saucer retaining portion forming the base of the rack and being so constructed as to provide an inclined floor whereby the saucers are easily slipped along the floor and 45 along the upper surface of the adjacent lower saucer respectively, when placed in stacked relation.

These and other objects and advantages of the 50 invention will appear from the following disclosure thereof together with the attached drawings which illustrates certain forms of embodiments thereof. These forms are shown for the purpose of illustrating the invention since the same has been found in practice to give satisfactory and reliable results, although it is to be

understood that the various instrumentalities of which the invention consists can be variously arranged and organized and that the invention is not limited to the precise arrangement and organization of the instrumentalities as herein shown and described.

In the drawing:

Fig. 1 is a front view of a rack made in accordance with the invention;

Fig. 2 is a side view thereof;

Fig. 3 is a top view thereof;

Figs. 1 to 3 disclose the invention in one of its many forms in which numeral 10 indicates a 15 base or frame portion upon which is secured an extended handle 11. Base 10 and handle 11 may be formed of wire by suitable bending operations, the handle 11 being in this instance welded or soldered to base or frame portion 10 as indicated 20 at 12.

Base 10 has a plurality of legs 13, 14, 15 forming a tripod. Legs 13, 14 are joined together by a raised bar 16 and the rear leg 15 is connected to said bar 16 by a bar 17 constituting a slanting frame-like or skeleton support 18 to accommodate such articles as saucers or plates 19 in stacked relation placed within the rack through the open preferably rectangularly shaped front portion 20. Since the skeleton floor or support 18 slants downwardly from said front portion towards the rear a saucer or plate A when inserted through opening of front portion 20 will slide towards the rear, abut against the rear leg extension 15a and will be guided between the 25 front upright portions 13a and 14a. The next plate or saucer B is placed in contact with said plate and permitted to slide thereon, the latter acting as an inclined plane upon which the former will slide. Thus the plates or saucers 30 A, B, C etc. are very easily and conveniently inserted and maintained in stacked relation within the base or frame portion 10 of the rack, the vertical extensions 13a, 14a and 15a of the respective legs 13, 14 and 15 acting as retaining members for confining the saucers within the base or frame portion 10.

The elongated handle 11 preferably consists of a pair of parallelly spaced wires 21, 22 bent in the form of inverted U's, these wires being held in spaced relation preferably by cross members 23 secured to the hand-gripping portions or grasping means 24, 25 of the handle 11 and by being secured to the frame of skeleton platform 26 at 12. Platform 26 is welded, soldered or 35

otherwise secured to the respective horizontal extensions 13b, 14b, 15b of said extensions of legs 13, 14 and 15. The inner portions 27, 28 of said wires 21, 22 function as guides for receiving the 5 ears 29a of the cups 29 as they are stacked on platform 26 in staggered relation.

Fig. 1 clearly shows how the cups 29 are positioned one over the other with their respective ears 29a, 29b etc. in staggered relation and between 10 the frame portions 27, 28. In order to provide a suitable seat for the stack on platform 26, there is provided a cushion 31 made of rubber, cork, felt or other suitable frictional means.

Fig. 4 shows a modified form of base frame 10 15 wherein the front upright portions 32a, 33a of legs 32, 33 are somewhat inclined and joined at their upper ends by a cross piece 34 providing a reinforcement for platform 35. The rear leg 36 is bent inwardly at its upper end as indicated at 20 37 and is secured to platform 35 at 38, 39.

In both instances (Figs. 3 and 4) the platform consists of a substantially circular wire ring 26 and 35, respectively, to which an annulus 40 made of wire is concentrically arranged. Ring and 25 annulus are connected with one another by bridging members, as indicated by numerals 41, 42 (Fig. 3) and 43 (Fig. 4). According to Fig. 4 reinforcing bridging members of platform 35 also are formed by cross piece 34 and extension 37.

30 The skeleton compartment formed by base or frame portion 10 and which is shown in the drawing as retaining the plates A, B, C etc. may be employed and, if necessary, modified for any convenient purpose, for example, to support therein 35 such culinary articles, as knives, forks, spoons, etc. The articles placed in said compartment will then function as ballast to stabilize the rack.

It will be observed that the inclined formation of the skeleton support or floor of the compartment of base or frame portion 10 contributes to 40 the safe retention of the articles placed therein, for the tendency of the latter is to abut against the rear leg extension in said compartment particularly during carrying of the rack from place 45 to place, even when swung during transportation.

From the above description it will be apparent that there is thus provided a device of the character described comprising a frame portion for holding articles, such as saucers, therein, means 50 for retaining said saucers against accidental lateral displacement in said frame portion, a platform forming part of said frame portion for holding articles, such as cups, thereon, means extending upwardly from said platform for engaging the ears of said cups to maintain said cups in position on said platform, and grasping means located substantially above said upwardly extending means for carrying said rack. The above described rack or device possesses the particular features of advantages before enumerated 55 as desirable, but which obviously is susceptible of modification in its form, proportions, detail construction and arrangement of parts without departing from the principle involved or sacrificing any of its advantages.

While there has been shown and described and

pointed out the fundamental novel features of the invention as applied to the above embodiments, it will be understood that various admissions and substitutions and changes in the form and details of the device illustrated and its operation may be made by those skilled in the art without departing from the spirit of the invention. 5

Having thus described the invention what is claimed as new and desired to be secured by Letters Patent is:

1. A rack for cups and saucers comprising a frame portion for holding saucers therein, means for retaining said saucers against accidental lateral displacement in said frame portion, a platform forming part of said frame portion for holding cups thereon, means extending upwardly from said platform for engaging the ears of said cups to maintain said cups in position on said platform, and grasping means located substantially above said upwardly extending means for carrying said rack. 20

2. A rack of the character described comprising a frame portion, a platform adjacent said frame portion, said frame portion comprising a compartment for holding articles, such as saucers, in stacked relation, means for retaining said saucers against accidental lateral displacement in said compartment, and slotted means extending from said frame portion, said platform being adapted 30 for maintaining articles, such as cups, in stacked relation and with the ears of said cups in engagement with said slotted means.

3. A rack of the character described comprising a handle portion, a base portion, and a platform intermediate said portions, said handle portion comprising a pair of spaced apart substantially parallelly disposed U-shaped members having their ends secured to said platform, said base portion comprising a compartment for holding 40 articles, such as saucers, in stacked relation, said platform being adapted for maintaining articles, such as cups, in stacked relation and with their ears within the space between said members, said compartment being provided with an inclined support on which said saucers may be 45 stacked.

4. A rack of the character described comprising a handle portion, a base portion, and a platform intermediate said portions, said handle portion comprising a pair of spaced apart substantially parallelly disposed U-shaped members having their ends secured to said platform, said base portion comprising a compartment for holding articles, such as saucers, in stacked relation, said 50 platform being adapted for maintaining articles, such as cups, in stacked relation and with their ears projecting within the space between said members, said compartment being provided with a substantially rectangular front portion having 55 an opening through which said saucers may be inserted within said compartment and being provided with a substantially U-shaped rear portion against which said saucers may abut when so inserted. 60
